UNITED STATES PATENT OFFICE

2,577,649

SPEED ADJUSTMENT FOR PHONOGRAPH TURNTABLES

Colin B. Dale, Oak Park, Ill., assignor to Webster-Chicago Corporation, Chicago, Ill., a corporation of Illinois

Application January 3, 1951, Serial No. 204,167

7 Claims. (Cl. 74—207)

1

This invention relates to a phonograph pitch control whereby a very fine adjustment may be obtained in the operating speed of its turntable and of the disc record which is rotated therewith. The range of speed adjustment is relatively small, perhaps only enough to cover a note or two in the musical scale, but ample for raising or lowering the pitch of the reproduced sounds which are given forth by the phonograph.

A primary purpose served by the present adjustment means is to bring the pitch of the reproduced sounds, particularly musical notes, into perfect harmony with that of an accompanying instrument, so that the two may be played together if desired. The invention is applicable to phonographs which have operating speeds for playing records of different diameters, the most common at the present being 33½, 45 and 78 r. p. m. In some respects the adjustment may be likened to that of a vernier control inasmuch as it operates within narrow limits to produce a very fine adjustment which is extremely accurate.

A suggestive embodiment of this invention is illustrated in the accompany drawing wherein:

Figure 1 is a fragmentary plan view of a phonograph equipped with the present pitch control, the turntable being partly broken away to exhibit a conventional three-speed drive mechanism therefor;

Fig. 2 which is a similar view shows the base platform of the turntable also broken away to exhibit in elevation the pitch control for the turntable;

Fig. 3 is a fragmentary perspective view showing the pitch control in connection with a turntable drive utilizing a single idler wheel intermediately of the drive shaft and friction wheel which drives the turntable;

Fig. 4 is a similar view showing the drive shaft in direct engagement with the friction wheel, thereby dispensing with any intermediate idler wheel in the transmission;

Fig. 5 is a fragmentary vertical sectional view showing a conventional motor and the bearings therefor in operative relation to a driven friction wheel having a shiftable mounting; and

Fig. 6 is a semi-diagrammatic view showing the friction wheel and its mounting in operative relation with the present pitch control.

In the drawing there is illustrated so much of a phonograph turntable T and operating mechanism therefor as is necessary to an understanding of the invention. The turntable which is formed with a depending marginal flange 1 is

mounted to rotate within a circular well 8 that is provided in the usual base B in the form of a platform which carries on its top face a speed control handle S and also a pitch control handle P for the adjustment that is special to this invention.

The operating mechanism for the turntable may include the driving end portion of the shaft 10 forming part of a motor M (see Fig. 5) which is journaled for rotation within spaced bearings 11 and 12 wherein the shaft is laterally supported; a plurality of stepped idler wheels 14, 15 and 16 having different diameters; and a friction wheel 18. These several parts are accommodated below the platform B or within the space between the turntable and platform, all of them being mounted to rotate about vertical axes. The idler wheels are carried upon a movable mount which is operable to position any selected idler between the shaft 10 and friction wheel 18 to transmit therethrough motion at a desired speed from the power shaft to the friction wheel which normally remains in engagement with the flange 1 of the turntable. This form of change speed drive is typical of several that may be employed in connection with the present invention; in fact a single speed drive, with or without an intermediate idler wheel, may optionally be used (see Figs. 3-6).

The friction wheel 18 is provided with a bushing 19 constituting therefor a bearing that is journaled for rotation upon a post 20 which upstands from an arm 21 at a point near one end thereof; the opposite arm end is provided with a slot 22, extending longitudinally of the arm, to receive a pivot pin 23 which upstands from the platform B to form a pivotal-sliding connection for the arm such that it may float within narrow limits to assure effective engagement of the friction wheel with the associated elements in the transmission of power. A tension spring 25 interconnects the mounting arm 21 near its free end with the weight end of a lever L, here shown as of the first class, that is fulcrumed to rock upon a pivot pin 26. The axis of this spring is disposed intermediately of the points where the friction wheel 18 is in driving engagement with the turntable flange (at the point a) and is itself drivingly engaged (at the point b) by one of the several idler wheels 14, 15 and 16 comprised in the change speed drive of Figs. 1 and 2, or by the single idler wheel 28 of Fig. 3, or directly by the power shaft 10 of Figs. 4-6.

The pull exerted by this spring upon the mounting arm is in the direction requisite for main-

taining an effective pressure in the frictional driving engagement between the wheel 18 and the turntable flange 1 and also an effective pressure in the frictional driving engagement between the shaft 10 (or one of the idler wheels driven thereby) and the same wheel 18, thereby to assure a steady transmission of motion therethrough to the turntable. Normally the tension of this spring is light so as to minimize the lateral pressure between (1) the bearing of the turntable T and the mounting therefor, (2) the tread of the wheel 18 and the turntable flange, (3) the bearing 19 of the wheel 18 and the post 20 whereon it is journaled for rotation, (4) the motor shaft 10 and its bearings 11 and 12, and (5) the bearing of any idler which is interposed in the wheel train and the part thereof that is journaled for rotation. The direction of spring pull in relation to (1) the points of wheel engagement *a* and *b*, and (2) the sliding-pivotal mounting at 23 of the arm 21, involves a toggle action in which but a slight tension on the part of the spring 25 produces an amplified pressure at the engagement points *a* and *b*.

As indicated in Fig. 3, the power end of the lever L is doubled back upon itself to a short upper ply 31 which is horizontally extended and apertured to receive the pivot pin 26 to stabilize the mounting for the lever. The upper ply 31 along one of its edges at the power end affords a convenient point for the application thereto of a variable power force which is transmitted from a cam 32 that is mounted fast on a rotatable pin 34 to which the pitch control handle P is also affixed. The contour of this cam is shown to be that of a spiral so that in one extreme rotative position the power end of the lever is relatively close to the axis of the pin 34, whereas in the opposite extreme rotative position it is relatively remote therefrom; also the fulcrum point 26 for the lever L is shown as relatively close to its power end so that the movement of its weight end is amplified with the result that in one adjusted position the spring 25 exerts but a relatively light tension, whereas in its opposite adjusted position the spring exerts a relatively heavy tension such as to increase noticeably the friction which obtains between (1) the turntable T, (2) the friction wheel 18, (3) the motor shaft, and (4) the idlers (if any) comprised in the wheel train, and their respective rotatable mountings. In Fig. 6 an exaggerated showing is made of the direction and extent of movement of the friction wheel 18 and power shaft 10 in response to braking of the drive mechanism in the manner already described. The cam control for operation of the lever, however, permits a very fine adjustment to be made, the lever being shiftable to any selected position within its range of movement and being there maintained due to the constant tension of the spring 25 which exerts its force reactively to hold the parts motionless through an indefinite period.

By the means described, I have provided what amounts to a vernier speed adjustment which is effective through imposition of a variable frictional pressure at the bearings of the several parts comprised in the transmission of power to the turntable to control accurately although narrowly, the operating speed of the latter. Any slight change in such operating speed will, in consequence, raise or lower the pitch of the reproduced sounds emanating from the phonograph. In this way it is possible to bring the pitch into exact harmony with an accompanying

piano or other instrument, thereby rendering the phonograph useful under conditions where otherwise its operation would be wholly unacceptable.

I claim:

5. 1. In a phonograph turntable drive of the type which utilizes a driven wheel in frictional engagement with a marginal flange depending from the turntable, the friction wheel being carried on a mounting which is shiftable transversely of the axis of the turntable to vary the position of the friction wheel relative to its flange, the feature of improvement which comprises a lever of the first-class mounted to swing its weight end toward and from the wheel axis, 10 a tension spring interconnecting the weight end of the lever and the wheel mounting at a point adjacent the wheel axis, the lever at its power end being reversely bent to provide a doubled-back portion, a post constituting a fulcrum for 15 the lever traversing an aperture therein and also an aperture in the doubled-back portion of the lever, and a cam in engagement with the lever at its power end for operation thereof, counter to tension of the spring, to a selected distant 20 position relative to the wheel axis, thereby to determine the tension of the spring and of the force transmitted therethrough to the mounting transversely of the axis of wheel rotation.

2. In a phonograph turntable drive of the type 30 which utilizes a driving wheel coacting frictionally with a driven wheel in frictional engagement with a marginal flange depending from the turntable, together with an elongated rigid mounting whereon near one end thereof the driven wheel 35 is journaled for rotation, the mounting near its opposite end being pivotally and slidably movable transversely of the axis of the turntable eccentrically thereof to simultaneously vary the position of the driven wheel relative to both the driving wheel and to the turntable flange, the feature of improvement which comprises a rigid lever disposed beyond the confines of the turntable and mounted to swing its weight end toward and from the driven wheel axis, a tension 40 spring interconnecting the said lever and the driven wheel mounting at a point adjacent the axis of the driven wheel so disposed as to exert its pulling force on the mounting intermediately of the driving and driven wheels, and a cam in 45 engagement with the lever for operation thereof, counter to tension of the spring, to a selected distant position relative to the driven wheel axis, thereby to determine the tension of the spring and of the force transmitted therethrough to 50 the mounting transversely of the axis of the driven wheel.

3. In a phonograph turntable drive of the type 60 which utilizes a driving wheel coacting frictionally with a driven wheel in frictional engagement with a marginal flange depending from the turntable, together with an elongated rigid mounting whereon near one end thereof the driven wheel 65 is journaled for rotation, the mounting near its opposite end being pivotally and slidably movable transversely of the axis of the turntable eccentrically thereof to simultaneously vary the position of the driven wheel relative to both the driving wheel and to the turntable flange, the feature of improvement which comprises a rigid lever disposed beyond the confines of the turntable and mounted to swing its weight end toward and from the driven wheel axis, a tension 70 spring connecting the said lever end at a point relatively distant from the fulcrum with the driven wheel mounting at a point adjacent the 75

axis of the driven wheel and so disposed as to exert its pulling force on the mounting intermediately of the driving and driven wheels, and a cam in engagement with the lever at a point relatively close to the fulcrum and operable to impart an amplified movement to the weight end of the lever, counter to tension of the spring, to a selected distant position relative to the driven wheel axis, thereby to determine the tension of the spring and of the force transmitted therethrough to the mounting transversely of the axis of the driven wheel.

4. In a phonograph turntable drive of the type which utilizes a driving wheel coacting frictionally with a driven wheel in frictional engagement with a marginal flange depending from the turntable, the driven wheel being carried on an elongated rigid mounting, near one end thereof, which is shiftable transversely of the axis of the turntable to simultaneously vary the position of the driven wheel relative to both the driving wheel and to the turntable flange, the feature of improvement which comprises a rigid lever of the first class disposed beyond the confines of the turntable and mounted upon a fulcrum to swing its weight end toward and from the driven wheel axis, a tension spring interconnecting the lever weight end and the wheel mounting at a point adjacent the axis of the driven wheel and so disposed as to exert its pulling force on the mounting intermediately of the driving and driven wheels and a cam in engagement with the power end of the lever for operation thereof, counter to tension of the spring, to a selected distant position relative to the driven wheel axis, thereby to determine the tension of the spring and of the force transmitted therethrough to the mounting transversely of the axis of the driven wheel.

5. In phonograph turntable drive of the type which utilizes a driving wheel coacting frictionally with a driven wheel in frictional engagement with a marginal flange depending from the turntable, the driven wheel being carried on an elongated rigid mounting, near one end thereof, which is shiftable transversely of the axis of the turntable to simultaneously vary the position of the driven wheel relative to both the driving wheel and to the turntable flange, the feature of improvement which comprises a rigid lever of the first class disposed beyond the confines of the turntable and mounted upon a fulcrum to swing its weight end toward and from the driven wheel axis, a tension spring connecting the lever weight end at a point relatively distant from the fulcrum with the wheel mounting at a point adjacent the driven wheel axis and so disposed as to exert its pulling force on the mounting intermediately of the driving and driven wheels, and a cam in engagement with the power end of the lever at a point relatively close to the fulcrum and operable to impart an amplified movement to the weight end of the lever, counter to tension of the spring, to a selected distant position relative to the driven wheel axis, thereby to determine the tension of the spring and of the force transmitted therethrough to the mounting transversely of the axis of the driven wheel.

6. In a phonograph turntable drive of the

type which utilizes a driving wheel coacting frictionally with a driven wheel in frictional engagement with a marginal flange depending from the turntable, the driven wheel being carried on an elongated rigid mounting, near one end thereof, which is shiftable transversely of the axis of the turntable to simultaneously vary the position of the driven relative to both the driving wheel and to the turntable flange, the feature of improvement which comprises a rigid lever of the first class disposed beyond the confines of the turntable and mounted to swing its weight end toward and from the driven wheel axis, a tension spring interconnecting the weight end of the lever and the wheel mounting at a point adjacent the driven wheel axis and so disposed as to exert its pulling force on the mounting intermediately of the driving and driven wheels, a pivotally mounted cam in engagement with the lever for operation thereof, and a pitch control handle connected fast with the cam for operation thereof, the cam, when operated, acting to swing the lever, counter to tension of the spring, to position its weight end at a selected distant point relative to the driven wheel axis, thereby to determine the tension of the spring and of the force transmitted therethrough to the mounting transversely of the axis of the driven wheel.

7. In a phonograph turntable drive of the type which utilizes a driving wheel coacting frictionally with a driven wheel in frictional engagement with a marginal flange depending from the turntable, together with an elongated rigid mounting whereon near one end thereof the driven wheel is journaled for rotation, the mounting near its opposite end being pivotally and slidably movable transversely of the axis of the turntable eccentrically thereof to vary the position of the driven wheel relative to both the driving wheel and to the turntable flange, the feature of improvement which comprises a rigid lever disposed beyond the confines of the turntable and mounted to swing its weight end toward and from the driven wheel axis, a tension spring interconnecting the said lever end and the wheel mounting at a point adjacent the axis of the driven wheel and so disposed as to exert its pulling force on the mounting intermediately of the driving and driven wheels, and a manually adjustable motion-transmitting means in engagement with the lever for operation thereof, counter to tension of the spring, to a selected distant position relative to the driven wheel axis, thereby to determine the tension of the spring and of the force transmitted therethrough to the mounting transversely of the axis of the driven wheel.
